6 Claims. (Cl. 112—158)

The present invention relates to a zigzag stitch sewing machine, and concerns particularly a device for regulating the direction and size of the lateral throw of the needle.

The main object of the invention is to mount the control members in such a way that a lateral displacement of the zigzag stitching can be effected without altering the size of the stitch. Another object is to make the adjusting means easy to read, and to make it, together with the mechanism controlled by it, as compact as possible.

Referring to the drawings, in which an illustrative embodiment of the invention is shown,

Figures 1 to 3 show one adjustment of the parts for a quilting seam in the middle of the stitching range; Figures 4 to 6 show an adjustment of the parts for a quilting seam at one side of the middle of the stitching range. In particular,

Fig. 1 is a vertical section taken behind the setting lever.

Fig. 2 is a vertical section taken in front of the setting lever, with the cap removed.

Fig. 3 is a front elevation of the device with all parts assembled.

Figs. 4, 5 and 6 are views respectively similar to Figs. 1, 2 and 3, with the setting lever shifted to another position.

Fig. 7 is a vertical section along the axis of the bearing for the shaft of the grooved cam.

Fig. 8 is a plan view of the cap.

Fig. 9 is a stitch diagram.

The invention is illustrated in the form of an improvement upon the needle controlling mechanism disclosed in prior patent to Böltter, dated June 23, 1936, No. 2,045,340; similar parts being identified by the same reference characters, namely, the grooved cam 8 and the setting handles 9 and 12.

Upon a base plate 31 is rotatably mounted a rotary bearing 10, to which is rigidly fixed by a screw 3 a plate 54 having attached to it a setting lever 12 which serves to shift the base line on which the needle operates.

In the bearing 10 a shaft 33 is rotatably mounted eccentrically to the axis of the bearing. The inner end of the shaft 33 bears a grooved cam 8. Upon the outer end of the shaft 33 a toothed segment 51 is fastened by means of a set screw 52. With this toothed segment 51 meshes a broad pinion 53, which is mounted by a pin 55 upon the plate 54 of the setting lever 12. The toothed segment 51 has a one-sided extension 56, in which a cam slot 57 is cut. In the cam slot 57 engages a

guide pin 62, which is riveted to the base plate 31. A pointer disc 59 is fixed to the reduced front end of the pinion member 53 by a set screw 4 passing through its hub 58. The hub has a downwardly extending adjusting handle 9 for regulating the size of the zigzag stitches.

The two setting positions of the setting lever 12 are determined by two notches 61 of a cap 62a mounted by screws 5 upon the base plate 31. The cap 62a has upon it two scales 63 and 64, only one of which is visible at a time, because the other is covered by the pointer disc 59.

The device described operates in the following manner: When the setting lever 12 is in the position shown in Fig. 3, the scale 64 is visible. If the adjusting handle 9 is set to the zero position of the scale, a quilting stitch in the middle of the stitching range results, as shown at the top of Fig. 9. By changing the position of the adjusting handle 9, the size of the zigzag stitches extending from the middle toward both extremities of the stitching range can be increased.

When the setting lever 12 is shifted from the position shown in Fig. 3 to the position shown in Fig. 6, at first there is no rotation of the toothed segment 51 and the pinion 53 about their own axes, because of the simultaneous swinging of the shaft 33 and pin 55 about the axis of the bearing 10. However, by this swinging motion the angular position of the grooved cam 8 is changed, so that an alteration of the size of the stitch would result if the former angular position were not restored by a subsequent backward adjustment. This backward adjustment is taken care of by the particular form of the cam slot 57 working in combination with the pin 62.

For instance, if the pin 62 has assumed the position shown at 65 in dotted lines in Fig. 2, as a result of its relative motion within the cam slot 57, further rotation of the setting lever 12 will cause a combined swinging and turning motion of the parts 53 and 51, because the pin 62 glides in the cam slot 57 from the position 65 toward the position 66, also indicated by dotted lines in Fig. 2. By this movement the pointer disc 59 is displaced from the position shown in Fig. 3 to the position shown in Fig. 6, thereby uncovering the scale 63 and covering the scale 64.

By changing the setting of the setting lever 9, an angular adjustment of the slotted guide 8 is accomplished through the action of the pinion 53 and toothed segment 51, which causes

a relative motion of the pin 62 from position 66 to position 67, also shown in dotted lines in Fig. 2. This adjustment changes the size of the quilting or zigzag stitches which lie along the left, according to the middle diagram of Fig. 9.

If the device has been set for a certain width of stitches for the zigzag seam, by a mere shifting of the setting lever 12 the same zigzag stitch 10 can be displaced without changing its size, as shown in the lower part of Fig. 9.

We claim:

1. In a needle vibration controlling means for zigzag stitch sewing machines, an angularly adjustable grooved cam for controlling the lateral throw of the needle, means comprising a rotatable member for shifting said cam along an arcuate path to change the origin of the lateral throw of the needle, and means effective during the shifting of said cam for angularly adjusting said cam to compensate for the angular movement which would otherwise be imparted to it by its shifting, thereby retaining the same amplitude of lateral throw of the needle.
2. In a needle vibration controlling means for zigzag stitch sewing machines, a bearing member mounted to rock on a fixed axis, a grooved cam mounted eccentrically on said bearing member so as to be capable of angular adjustment about an axis parallel to the axis of said bearing member, means for rocking said bearing member, means for angularly adjusting said cam, and means engaging said last means to restrain it from incorrect movement when said bearing member is rocked, thereby to prevent angular movement of said cam.
3. In a needle vibration controlling means for zigzag stitch sewing machines, an angularly adjustable groove cam for controlling the lateral throw of the needle, means for moving said cam bodily along an arcuate path to change the origin of the lateral throw of the needle, mechanism including a crank connected to said cam for adjusting the latter angularly to change the extent of lateral throw of the needle, and means

engaging said crank to restrain the same as said cam is moved bodily, thereby to turn said crank to compensate for the angular movement which would otherwise be imparted to said cam.

4. In a needle vibration controlling means for zigzag stitch sewing machines, an angularly adjustable grooved cam for controlling the lateral throw of the needle, a pivoted setting member on which said cam is mounted, a toothed segment positively connected to said cam, a pinion 10 rotatably mounted on said setting member meshing with said toothed segment, and manipulative means for rocking said pinion.

5. In a needle vibration controlling means for zigzag stitch sewing machines, an angularly adjustable grooved cam for controlling the lateral throw of the needle, a pivoted setting member on which said cam is mounted, a toothed segment positively connected to said cam, a pinion rotatably mounted on said setting member meshing with said toothed segment, manipulative means for rocking said pinion, a cam segment 20 connected to said toothed segment, and a stationary pin engaging said cam segment to control the angular movement of said toothed 25 segment and the cam connected thereto.

6. In a needle vibration controlling means for zigzag stitch sewing machines, an angularly adjustable grooved cam for controlling the lateral throw of the needle, a pivoted setting member 30 on which said cam is mounted, a toothed segment positively connected to said cam, a pinion rotatably mounted on said setting member meshing with said toothed segment, manipulative means for rocking said pinion, a cap covering 35 said segment and pinion, a shaft projecting rigidly from said pinion through said cap, manipulative means secured to said shaft in front of said cap and comprising a cover plate and pointer, said cap having thereon two separate scales alternately covered by said cover plate as said setting member is moved from one position to another.
